UNITED STATES PATENT OFFICE

ALFRED J. HEINKE, OF TOWACO, NEW JERSEY

DESIGN FOR A TEXTILE FABRIC OR SIMILAR ARTICLE OF MANUFACTURE

Application filed October 8, 1932. Serial No. 45,260. Term of patent 3½ years.

To all whom it may concern:

Be it known that I, ALFRED J. HEINKE, a citizen of the United States and resident of Towaco, in the county of Morris and State of New Jersey, have invented a new, original, and ornamental Design for Textile Fabric or Similar Article of Manufacture, of which the following is a specification, reference being had to the accompanying drawing, forming a part thereof, and showing a face view of a piece of textile fabric embodying my design, the shading indicating contrast in color.

A repeat unit occurs in the diagonal relation shown, the lines A—A and B—B being used to aid in following the direction.

I claim:

The ornamental design for a textile fabric or similar article of manufacture substantially as shown and described.

Signed at New York, in the county of New York and State of New York, this 7th day of October A. D. 1932.

ALFRED J. HEINKE.
